(57) **CLAIM**

The ornamental design for an ambience lamp, as shown and described.

DESCRIPTION

FIG. 1 is a front elevational view of an ambience lamp according to one embodiment of the claimed design;
FIG. 2 is a rear elevational view thereof;
FIG. 3 is a left-side elevational view thereof;
FIG. 4 is a right-side elevational view thereof;
FIG. 5 is a top view thereof; and,
FIG. 6 is a bottom view thereof.

The broken line disclosure represents portions of the lamp which form no part of the claimed design.
